FIELD CORRECTION IN MAGNETIC
INDUCTION ACCELERATORS

Willem F. Westendorp, Schenectady, N. Y., assignor to General Electric Company, a corporation of New York

Application August 29, 1950, Serial No. 182,025

6 Claims. (Cl. 250—27)

1

The present invention relates to magnetic induction accelerator devices and, more particularly, to means for increasing the efficiency with which charged particles may be accelerated in such devices.

Apparatus for accelerating charged particles by means of magnetic induction effects is described and shown in my prior Patents 2,394,071, 2,394,072 and 2,394,073, all of which were issued February 5, 1946, and assigned to the General Electric Company, a corporation of New York. Such apparatus generally comprises a core of magnetic material including a pair of opposed rotationally symmetrical pole pieces which define a toroidal gap wherein an evacuated annular container is positioned. The core is excited by means of windings which are energized by a source of time-varying voltage to produce a time-varying magnetic flux which links an orbital path within the evacuated container and a time-varying magnetic guide field which traverses the orbital path. Charged particles, injected into the orbital path from a suitable source positioned adjacent thereto, are accelerated by the time-varying magnetic flux during a great number of revolutions to high energy levels while the time-varying magnetic guide field constrains the particles to the orbital path.

As has been denoted in my prior patents, it is essential that the time-varying magnetic guide field existing between pole faces of the rotationally symmetrical pole pieces have a nearly constant inverse slope with radius or radial displacement in order that the charged particles may be accelerated along a stable orbit. This condition is very often difficult to fulfill because field assymmetries many times result from imperfect core and pole piece construction. Furthermore, in order that the charged particles may execute a number of revolutions within a stable orbit near the center of the evacuated container, it is necessary that the magnetic lines of force between the pole faces of the opposed rotationally symmetrical pole pieces be perpendicular to the plane of symmetry of the annular container. Very often imperfect core and pole piece construction also results in the magnetic lines of force between the pole faces being perpendicular to a plane above or below the plane of symmetry of the annular container whereby the charged particles are prematurely discharged upon the walls of the annular container.

According to one feature of the invention more fully described and explained hereinafter, a set

5 of single-turn, electrically separate, circular coils is attached to the pole face of each of the rotationally symmetrical pole pieces and, in circuit with each of these coils, is placed a variable 10 resistor. When the magnetic core including the pole pieces is energized, the time-varying magnetic flux which links each of the circular coils will induce a voltage therein, and since a separate circuit for each of the coils is formed through its respective variable resistor, each of 15 the coils will carry a current having a magnitude dependent upon the number of flux linkages and the respective circuit constants. The current induced in each coil may be varied in magnitude by the variable resistor in circuit therewith whereby the field existing between the rotationally symmetrical pole faces may be suitably modified by trial and error to provide a desired field configuration free of the defects, herein- 20 before mentioned, resulting from imperfect core and pole piece construction.

The features which I desire to protect herein are pointed out with particularity in the appended claims. The invention itself, together 25 with further objects and advantages thereof, may best be understood by reference to the following description taken in connection with the accompanying drawings in which Fig. 1 is a partially sectionalized view of an induction accelerator suitably embodying my invention; Fig. 30 2 is an enlarged sectionalized fragmentary view of the injector structure of Fig. 1; Fig. 3 is an enlarged fragmentary view of the pole pieces of the apparatus of Fig. 1; Fig. 4 is a graphical representation useful in explaining the invention and Figs. 5, 6 and 7 are schematic illustrations showing circuit connections for the coils attached to the pole faces of the accelerator apparatus.

40 Referring particularly to Fig. 1, there is shown exemplary magnetic induction accelerator apparatus comprising a magnetic core 1 which may be laminated to minimize the generation of eddy currents therein. Magnetic core 1 includes 45 laminated rotationally symmetrical opposed pole pieces 2 and 3 having generally outwardly tapered pole faces 4 and 5 for the provision of a magnetic guide field along an orbital path indicated at point x, as will be more fully described hereinafter. Coaxial with pole pieces 2 and 3 and disposed between pole faces 4 and 5 is an evacuated 50 annular container or vessel 6 of dielectric material which provides within its interior an annular chamber 7 wherein charged particles may be advantageously accelerated. The cen-

tral portions of pole pieces 2 and 3 are terminated respectively by flat surfaces 8 and 9 between which are disposed laminated metallic discs 10 and 11 and dielectric support spacers 12. Metallic discs 10 and 11 serve the purpose of reducing the reluctance of the magnetic path in the region between surfaces 8 and 9.

Magnetic core 1 may be excited from a suitable source of time-varying voltage 13 connected as indicated to series-connected energizing windings 14 and 15 surrounding pole pieces 2 and 3. To minimize the current drawn from the source 13, energizing windings 14 and 15 may be resonated by power factor correcting capacitors 16. Within chamber 7 there is provided a charged particle source, such as the electron gun 17 which is shown in more detail in Fig. 2. Gun 17 may comprise a housing member 18 within which is positioned a thermionic filament 19 partially enclosed by a shield member 20. Conductive wires 21 and 22, which may be connected to an intermittent source of electrical energy (not shown), are sealed as shown into a side arm 23 of container 6 and connected at their inner extremities respectively to filament 19 and housing member 18. More detailed illustration and description of suitable electron gun structure may be found by reference to my above mentioned prior patents.

As will be well understood by those skilled in the art, energization of windings 14 and 15 by the source of time-varying voltage 13 will result in a time-varying magnetic flux which traverses magnetic core 1 and pole pieces 2 and 3 to provide a time-varying magnetic flux which links orbital path x and a magnetic guide field which traverses the locus of the orbital path x between pole faces 4 and 5. Electrons emitted by gun 17 at a desired time instant near zero in the cycle of magnetic flux and field variations will be continuously accelerated as they execute repeated revolutions along orbital path x . As a consequence, the injected electrons may be caused to assume energies of many millions of electron volts and then may be automatically directed to impinge upon a target 24 to produce X-rays, the target being affixed to container 6 and a conductive coating 25 in a manner well known to those skilled in the art.

As has been mentioned heretofore, imperfect construction of core 1 including pole pieces 2 and 3 may result in the plane of the orbital path x being shifted above or below the plane of symmetry of the annular container 6. This effect is illustrated in Fig. 3 wherein dotted line 26 represents the plane of symmetry of annular container 6 while line 27 illustrates the plane which would include orbital path x when the magnetic lines of force existing between pole faces 4 and 5 have the curvature represented by dotted lines 28. The conventional designation in Fig. 3 of pole piece 2 as a south pole and pole piece 3 as a north pole is illustrative of the respective polarities of the pole pieces for the acceleration of electrons in a counterclockwise direction. It will be realized by those well skilled in the art that the orbital path, which electrons undergoing acceleration follow, always lies in a plane which is perpendicular to the magnetic lines of force between pole faces 4 and 5 as is illustrated by lines 27 and 28 of Fig. 3. Consequently, if the magnetic lines of force between pole faces 4 and 5 have an asymmetrical curvature, the stable orbital path along which the electrons are accelerated is shifted either above

or below the plane of symmetry of annular container 6 depending upon the direction of asymmetry. It will be apparent, therefore, that the stable orbital path may be shifted sufficiently above or below the plane of symmetry of annular container 6 so as to cause at least some of the electrons to impinge prematurely upon the walls of container 6 thereby reducing the efficiency of acceleration.

As has also been mentioned heretofore, imperfect core and pole piece construction may in addition cause undesirable radial variations of the field strength between pole faces 4 and 5. In magnetic induction accelerator apparatus as above described, electrons are accelerated in a stable manner only if the following relation is observed:

$$H \propto \frac{1}{r^n} \quad (1)$$

where H is the magnetic field strength between pole faces 4 and 5, r is the radius of the point under consideration, and n is a constant having a value lying between zero and unity. If this relation is properly fulfilled, then electrons may be accelerated in a stable manner as they oscillate within a limited region surrounding orbital path x . The value of the constant n usually is arranged to be approximately .75 as is indicated by the slope of curve 29 between points a and b of Fig. 4 wherein the magnetic field strength between pole faces 4 and 5 is plotted as a function of radius. Points a and b define the extremities of the region surrounding orbital path x within which electrons may be stably accelerated while points c and d define the extremities of pole faces 4 and 5. Very often, however, in the construction of the magnetic circuit of magnetic induction accelerator apparatus, the radial field distribution falls off in an undesired non-uniform manner as is indicated by dotted curve 30 of Fig. 4. This means that the above-stated stability relation is not fulfilled within the region surrounding orbital path x and a considerable reduction in the efficiency of the accelerator apparatus consequently occurs.

According to the present invention, both of these difficulties resulting from imperfect core and pole piece construction may be obviated by affixing with a suitable adhesive a plurality or set of single-turn, circular conductors or coils 31 along each of the pole faces 4 and 5. It has been found that, by connecting separate circuits to each of these conductors and properly adjusting the current flow therein, the magnetic field distribution between pole faces 4 and 5 may be corrected to increase the output of the above-described accelerator apparatus as much as one hundredfold.

Referring now to Figs. 5, 6 and 7, there are shown several circuit arrangements with which the above mentioned advantages of the present invention may be suitably realized. As is shown in Fig. 5, each of the single-turn conductors 31 may be connected in series with a variable resistor 32. With this arrangement, the magnetic flux linking the various conductors 31, when exciting windings 14 and 15 are energized by the source of time-varying voltage 13, will induce a voltage in each coil proportional to the time rate of change of enclosed flux, and the resultant current flow may be suitably adjusted by variable resistor 32. The current flowing in conductors 31 has a maximum amplitude when the

time-varying flux passes through zero and, therefore, has nearly maximum effect upon the field distribution when the electrons from gun 17 are injected and field symmetry is most important. The current flowing in conductors 31, of course, generates a magnetic field adjacent thereto which, with the proper consideration, will produce desired modification of the field between pole faces 5 and 6 in accordance with the invention. If, as illustrated in Fig. 3, the plane of orbital path x is too high, a desired modification of the magnetic field may be obtained by open-circuiting each of the coils 31 along pole face 4 by means of a switch 33 and then adjusting the current flow through each of the coils 31 along pole face 5 by means of each of the resistors 32. The desired lowering of the orbital plane is indicated by an increase in the X-ray output of the accelerator apparatus. If the magnetic field between pole pieces 4 and 5 does not fall off with radius in a uniform manner as required by Equation 1, correction may be obtained by closing the circuits of the coils 31 positioned on both pole faces 4 and 5 and adjusting the individual resistors 32 until an increase in the output in the accelerator apparatus is also obtained. It will be apparent that, if both of the magnetic field configuration deficiencies illustrated by Figs. 3 and 4 are present, a suitable compromise as to current flow in each of the conductors 31 may be found to produce maximum enhanced output. In general, the orbital plane may be shifted up or down by employing the set of coils 31 along either pole face 4 or pole face 5. With the connection of Fig. 5 the currents in the coils along pole face 4 and in the coils along pole face 5 are all in the same direction and, therefore, both sets of coils may be employed to produce the desired radial field configuration indicated by curve 29 of Fig. 4.

As shown in Fig. 6, each of the coils 31 may have connected in circuit therewith a fixed or variable resistor 34 and an autotransformer 35, the input of which may be connected to the source of time-varying voltage 13. With this arrangement, the voltage derived from autotransformers 35 and the time-varying voltage source 13 may be employed to oppose the voltage induced in each of the coils 31 and to produce a net voltage of opposite phase and of a desired magnitude across resistors 34 and coils 31 whereby the current in each of the coils 31 is in an opposite direction from that which would result from voltages induced therein by the time-varying flux. Conversely, net voltages of the same phase as the voltage induced in coils 31 may be obtained if the outputs of autotransformers 35 are respectively arranged to be slightly less than the voltages induced in coils 31. The arrangement of Fig. 6 permits the employment of the sets of coils 31 along both pole faces 4 and 5 to shift the plane of the orbit up or down; because, in order to shift the orbital plane up or down, either only one set of coils along the pole faces must be employed or the currents in the two sets must be in opposite directions. With the circuitry of Fig. 5 no current reversal in coils 31 is possible, while with the circuitry in Fig. 6 current reversal may be accomplished and hence both sets of coils 31 may be employed to shift the orbital plane.

It is also contemplated according to the present invention that direct current may be utilized to achieve the desired magnetic field modification. A circuit suitable for utilizing direct cur-

rent is shown in Fig. 7 wherein each of the coils 31 are illustrated as separately connected to a source of direct current (not shown) in series with an iron core reactor 36, a variable resistor 37 and a switch 38. Reactors 36 respectively serve to prevent a time-varying current from flowing in each of the coils 31 while the variable resistors 37 respectively serve to determine the amount of direct current which will flow in each of the circuits. It will be understood that the source of direct current may have the polarity indicated or the opposite polarity depending upon the requirements of the situation.

It will be realized by those skilled in the art that to secure desired correction of field inhomogeneities and asymmetries according to the present invention, the currents in the above-mentioned electrically separate coils may all be different from each other.

While the invention has been described by reference to particular embodiments, it will be understood that numerous modifications may be made by those skilled in the art without actually departing from the invention. I, therefore, aim in the appended claims to cover all such equivalent variations as come within the true spirit and scope of the foregoing disclosure.

What I claim as new and desire to secure by Letters Patent of the United States is:

1. Apparatus for accelerating charged particles comprising a closed vessel defining an annular chamber within which charged particles may move in a generally circular orbital path; a magnetic structure outside said vessel and including opposed, rotationally symmetrical pole pieces which are coaxial with said vessel; means for producing a time-varying magnetic field between said pole pieces, the pole pieces having outwardly tapered pole faces adjacent said vessel; means for projecting charged particles within said vessel; and means for causing the field between said outwardly tapered pole faces to conform to the proportionality

$$H \propto \frac{1}{r^n}$$

where H is the field intensity between said pole faces, r is the radial displacement and n is an exponent having a value lying between zero and one, and coincidentally therewith for causing the magnetic lines of force between the pole faces of said pole pieces to be perpendicular to the plane of symmetry of said vessel including a set of electrically separate current-carrying single-turn circular coils affixed to each of said pole faces.

2. Apparatus for accelerating charged particles comprising a closed vessel defining an annular chamber within which charged particles may move in a generally circular orbital path; a magnetic structure outside said vessel and including opposed, rotationally symmetrical pole pieces which are coaxial with said vessel; means for producing a time-varying magnetic field between said pole pieces, the pole pieces having outwardly tapered pole faces adjacent said vessel; means for projecting charged particles within said vessel; and means for causing the field between said outwardly tapered pole faces to conform to the proportionality

$$H \propto \frac{1}{r^n}$$

where H is the field intensity between said pole faces, r is the radial displacement and n is an

exponent having a value lying between zero and one, and coincidentally therewith for causing the magnetic lines of force between the pole faces of said pole pieces to be perpendicular to the plane of symmetry of said vessel including a set of single-turn circular current-carrying coils affixed to each of said pole faces, each of said coils being electrically separate and having connected thereto a separate circuit for determining the current flow in each coil.

3. Apparatus for accelerating charged particles comprising a closed vessel defining an annular chamber within which charged particles may move in a generally circular orbital path; a magnetic structure outside said vessel and including opposed, rotationally symmetrical pole pieces which are coaxial with said vessel, said pole pieces having outwardly tapered pole faces adjacent said vessel; means for projecting charged particles within said vessel; means for producing a time-varying magnetic field between said pole pieces; and means for causing the magnetic lines of force between the pole faces of said pole pieces to be perpendicular to the plane of symmetry of said vessel to correct for imperfect magnetic structure including a set of electrically separate circular coils affixed to one of said pole faces, each of said coils having in circuit therewith a resistor for limiting current flow through each of said coils resulting from the voltage induced therein by said time-varying magnetic field.

4. Apparatus for accelerating charged particles comprising a closed vessel defining an annular chamber within which charged particles may move in a generally circular orbital path; a magnetic structure outside said vessel and including opposed, rotationally symmetrical pole pieces which are coaxial with said vessel; means for producing a time-varying magnetic field between said pole pieces, the pole pieces having outwardly tapered pole faces adjacent said vessel; means for projecting charged particles within said vessel; and means for causing the field between said outwardly tapered pole faces to conform to the proportionality

$$H \propto \frac{1}{r^n}$$

where H is the field intensity between said pole faces, r is the radial displacement and n has a value lying between zero and one, and coincidentally therewith for causing the magnetic lines of force between the pole faces of said pole pieces to be perpendicular to the plane of symmetry of said vessel including a set of electrically separate circular coils affixed to each of said pole faces, each of said coils having connected in circuit therewith only a switch and a variable resistor.

5. Apparatus for accelerating charged particles comprising a closed vessel defining an annular chamber within which charged particles may move in a generally circular path; a magnetic structure outside said vessel and including opposed, rotationally symmetrical pole pieces

which are coaxial with said vessel; energizing windings upon said magnetic structure connected to a source of time-varying voltage for producing a time-varying magnetic field between said pole pieces, the pole pieces having outwardly tapered pole faces adjacent said vessel; means for projecting charged particles within said vessel; and means for causing the field between said outwardly tapered pole faces to conform to the proportionality

$$H \propto \frac{1}{r^n}$$

where H is the field strength between said pole faces, r is the radial displacement and n has a value lying between zero and one, and coincidentally therewith for causing the magnetic lines of force between the pole faces of said pole pieces to be perpendicular to the plane of symmetry of said vessel including a set of electrically separate single-turn circular coils distributed along the pole face of each of said pole pieces and a plurality of autotransformers, each of which has a secondary winding connected to one of said coils through a current-limiting resistor and a primary winding connected to said source of time-varying voltage.

6. Apparatus for accelerating charged particles comprising a closed vessel defining an annular chamber within which charged particles may move in a generally circular orbital path; a magnetic structure outside said vessel and including opposed, rotationally symmetrical pole pieces which are coaxial with said vessel; means for producing a time-varying magnetic field between said pole pieces, the pole pieces having outwardly tapered pole faces adjacent said vessel; means for projecting charged particles within said vessel; and means for causing the field between said outwardly tapered pole faces to conform to the proportionality

$$H \propto \frac{1}{r^n}$$

where H is the field between said pole faces, r is the radial displacement and n has a value lying between zero and one, and coincidentally therewith for causing the magnetic lines of force between the pole faces of said pole pieces to be perpendicular to the plane of symmetry of said vessel; including a set of electrically separate single-turn circular coils distributed along the pole faces of each pole piece, a source of direct current, and a separate circuit for each of said coils comprising a switch, a reactor and a resistor connected in series with each of said coils to said source of direct current.
